UNITED STATES PATENT OFFICE.

LYNN W. MACOMBER AND CHARLES H. JARVIS, OF BATTLE CREEK, MICHIGAN, AS
SIGNORS TO UNITED STEEL & WIRE COMPANY, OF BATTLE CREEK, MICHIGAN.

POULTRY CRATE.

Application filed June 4, 1928. Serial No. 282,560.

The main object of this invention is to provide an improved poultry shipping crate in which the bottom is securely retained when in assembled relation and at the same time 5 may be readily disassembled and assembled with the body of the coop as occasion may require.

Objects pertaining to details and economies of our invention will definitely appear from 10 the detailed description to follow. The invention is defined in the claims.

A structure which is a preferred embodiment of our invention is clearly illustrated in the accompanying drawing in which:

15 Fig. 1 is a side elevation of our improved poultry coop.

Fig. 2 is a detail view mainly in vertical transverse section on a line corresponding to line 2—2 of Fig. 1.

20 Fig. 3 is a fragmentary section on a line corresponding to that of Fig. 2 showing the manner of inserting or removing the bottom.

Fig. 4 is an enlarged detail section on a line corresponding to line 4—4 of Fig. 2.

25 In the embodiment illustrated in the drawing the body of the coop is designated generally by the numeral 1 and consists of suitable longitudinal bars, cross pieces and slats formed of wire or rods spot-welded together.

30 The coop body is formed with flaring side and end walls so that a plurality of them may be nested for shipment or storage, and this form also adds strength to the coop.

The bottom 2 is assembled as a unit and 35 is removably attached to the body, the bottom support consisting of pairs of spaced supporting bars 3 disposed in opposed relation to receive the edges of the bottom as shown in Fig. 2. The bottom has slots 4 and 5 in its edges to receive the stops 6 which are in the form of vertical wires welded to the supporting bars 3 and to the adjacent horizontal side bars 7.

40 Thus arranged the front edge of the bottom may be inserted between the supporting bars at one side and moved laterally, the slots 5 being of such depth as to permit the opposite edge to clear the bottom supporting bar on the opposite side when the bottom 45 is moved laterally in the opposite direction to the position indicated in Fig. 2.

To retain the bottom in this position we provide locking members 8 preferably formed of strips of metal having slides 9 looped at 50 10 to embrace adjacent vertical slats 11, there-

by slidably supporting the locking members so that they may be moved downwardly into the slots 5 and lock the bottoms in position.

The upper ends of the locking members project above the top slides providing finger-like catches 12 which are bent at 13 to engage the adjacent side bar 7. These catches automatically engage as the locking members are pushed downward to locking position. The lower ends of the locking members are 65 turned inwardly to provide a rounded head 14 facilitating the entry of the locking members in the slots 5.

The improved poultry crate is simple and economical in structure and the bottom may 70 be quickly inserted or removed, thus permitting the crates when empty to be shipped in the knockdown in nested condition, thereby greatly economizing on space and freight.

Having thus described our invention what 75 we claim as new and desire to secure by Letters Patent is:

1. A poultry crate comprising opposed pairs of spaced bottom supporting bars, a side bar disposed in spaced relation to the upper of one of said bottom supporting bars and slats the lower ends of which are connected to the bottom supporting bars, stops extending between said pairs of bottom supporting bars, a bottom having its opposite edges disposed between said bottom supporting bars and having slots in its edges alined with said stops, said slots being of such depth as to permit sliding of the bottom laterally 80 permitting engagement and disengagement thereof with the bottom bars, and bottom locking members having looped slat engaging slides adjustably supporting said locking members for engagement with slots in said bottom, the upper ends of said locking 85 members being extended above the upper slides thereof and conformed to provide spring catches coacting with said side bar for retaining the locking members in locking position.

2. A poultry crate comprising opposed pairs of spaced bottom supporting bars and slats, stops extending between said pairs of bottom supporting bars, a bottom having its opposite edges disposed between said bottom supporting bars and having slots in its edges alined with said stops, said slots being of such depth as to permit sliding of the bottom laterally 90 permitting engagement and disengagement thereof with the bottom bars, 100

105

110

and bottom locking members having slat engaging slides adjustably supporting said locking members for engagement with slots in said bottom.

- 5 3. A poultry crate comprising opposed pairs of spaced bottom supporting bars, a side bar disposed in spaced relation to the upper of said bottom supporting bars, and slats the lower ends of which are connected to the bottom supporting bars, a bottom having its opposite edges disposed between said bottom supporting bars for lateral adjustment therein permitting engagement and disengagement of the bottom with the bars, and a locking member having looped slat engaging slides whereby the locking member may be adjusted to bottom engaging position to prevent lateral disengaging movement thereof, the upper end of said locking member being extended above the upper slide providing a spring catch coacting with said side bar for retaining the locking member in locking position.
- 10 4. A poultry crate comprising opposed pairs of spaced bottom supporting bars, and slats, a bottom having its opposite edges disposed between said bottom supporting bars for lateral adjustment therein permitting engagement and disengagement of the bottom with the bars, and a locking member having slat engaging slides whereby the locking member may be adjusted to bottom engaging

position to prevent lateral disengaging movement thereof.

5. A poultry crate comprising bottom supporting members adapted to receive the opposite edges of the bottom and permitting lateral sliding adjustment thereof whereby the bottom may be engaged and disengaged with its supporting members, said crate having vertical slats above said bottom supporting members, and a bottom locking member having looped slat engaging slides whereby the locking member is supported for vertical adjustment to and from bottom engaging position, the upper end of said locking member constituting a spring catch, and a horizontal part on said crate with which said catch engages when the locking member is in locking position.

6. A poultry crate comprising bottom supporting members adapted to receive the opposite edges of the bottom and permitting lateral sliding adjustment thereof whereby the bottom may be engaged and disengaged with its supporting members, said crate having vertical slats above said bottom supporting members, and a bottom locking member supported for adjustment to and from bottom engaging position.

In witness whereof we have hereunto set our hands.

LYNN W. MACOMBER.
